DESIGN FOR A DRIP COFFEEPOT OR ANALOGOUS ARTICLE

Chauncey E. Waltman, Chicago, Ill., assignor to Porcelier Manufacturing Company, Greensburg, Pa., a corporation of Pennsylvania

Application December 17, 1935, Serial No. 60,132

Term of patent 3½ years

To all whom it may concern:

Be it known that I, Chauncey E. Waltman, a citizen of the United States, residing at Chicago, Cook County, State of Illinois, have invented a certain new, original, and ornamental Design for a Drip Coffeepot or Analogous Article, of which the following is a specification, reference being had to the accompanying drawing, forming a part thereof.

In the drawing:

or analogous article, embodying my design; and Figure 2 is a top plan view thereof.

In the drawing the dominant features of the design are shown in full lines. The opposite side of the article is substantially the same as that illustrated.

I claim:

The ornamental design for a drip coffeepot or analogous article, as shown and described.

CHAUNCEY E. WALTMAN.
